ENGINE

James W. Kinnucan, Detroit, Mich., assignor to
 Continental Motors Corporation, Detroit, Mich.,
 a corporation of Virginia

Application March 3, 1932, Serial No. 598,417

18 Claims. (Cl. 123—191)

This invention relates to internal combustion engines and refers more particularly to the general class of engines known as sleeve valve engines as distinguished from poppet valve engines.

5 My invention relates particularly to engines of the air cooled type but is not necessarily limited thereto.

Heretofore it has been customary to provide a cylinder head of the re-entrant type for sleeve valve engines, whereby to provide a sleeve pocket for shielding the upper or outer ends of the sleeve or sleeves. In such constructions the spark plug is located in the re-entrant portion of the cylinder head where it is not exposed to adequate cooling. Furthermore such usual location places the spark plug in the hottest part of the combustion chamber giving rise to difficulties from plug carbonization, overheating, and engine failure. Such disadvantages are of particular significance in air cooled sleeve valve engines such as may be used for aircraft or other purposes.

10 It is an object of my invention to overcome the aforesaid difficulties by the provision of a cylinder head especially adapted for air cooled sleeve valve engines, wherein I have avoided the usual recessed seat for the spark plug.

15 A further object of my invention resides in the provision of a cylinder head constructed to locate one or more spark plugs in the combustion chamber location which is usually occupied by the sleeve pocket, such location being the coolest part of the combustion chamber.

20 Further objects consist in the provision of an engine of the aforesaid types wherein an improved scouring action of the gases is obtained for the spark plug points from the swirling motion of the gases in the combustion chamber.

25 By reason of my improvements, the general performance and reliability of the engine is improved, the engine idles better, and the spark plugs are maintained cooler and more efficient.

30 A still further object of my invention resides in the provision of an improved combustion chamber for engines.

35 Further objects and advantages of my invention will be apparent as this specification progresses, reference being had to the accompanying drawing in which:

40 Fig. 1 is a sectional elevation view through a typical cylinder and cylinder head of the engine.

45 Fig. 2 is a sectional plan view along the line 2—2 of Fig. 1, and

50 Fig. 3 is a plan view of the cylinder head.

55 In the drawing reference character A represents a typical cylinder of the engine and in the em-

bodiment shown the cylinder 10 of the engine is subjected to a stream of cooling air represented by arrows 11, in Figs. 1 and 3 such as is customary for example in engines used in connection with aircraft or other purposes. The cylinder 10 is provided with cooling fins 12 and is also formed with one or more intake passages 13 for conducting the usual fuel mixture from intake manifold 14 to the various cylinder intake ports 15. Cylinder 10 is also provided with one or more exhaust ports 16 for conducting exhaust gases to the cylinder exhaust passage 17 and thence to the exhaust manifold 18.

5 My invention relates particularly to engines of the air cooled type but is not necessarily limited thereto.

10 Associated with cylinder 10 for controlling the intake and exhaust ports 15 and 16 is the sleeve valve means 19, and for purposes of illustration I have shown a single sleeve valve of the well known Burt-McCollum type in which sleeve intake and exhaust ports 20 and 21 respectively are adapted to cooperate with the corresponding cylinder ports in order to control the admission and exhaust of the gases to and from the combustion chamber. The sleeve valve 19 is adapted for combined reciprocating and oscillating movement in a manner well known in the art, and 15 since the particular type of sleeve movement is not a part of this invention I have not illustrated such details. Furthermore, it should be understood that any form of sleeve valve or like 20 means may be provided within the scope of my invention.

25 Seated on the upper or outer face of cylinder 10 is a cylinder head structure B preferably having an outer substantially flat floor 22 from which a plurality of cooling fins 23 extend outwardly for 30 exposure to the air stream.

30 A piston 24 is operably associated with the cylinder and preferably is fitted for movement within the sleeve valve 19, the usual connecting rod 25 extending to the crankshaft (not shown).

35 I preferably leave the outer portion or end of sleeve valve 19 exposed to the combustion chamber C whereby to provide an annular combustion chamber zone 26 adjacent the outer end of the cylinder walls. This zone 26 is thus located relatively from the cylinder axis X—X and is the coolest portion of the combustion chamber since it is located adjacent the walls of the cylinder 10. The cylinder head B is formed with one or more openings 27 adapted to receive a spark plug 28, 40 the openings 27 being located adjacent zone 26 whereby to position the spark plug terminals 29 at the zone 26 and therefore adjacent the outer walls of cylinder 10. I preferably provide two spark plugs 28 as shown in the illustration, these 45

plugs being substantially diametrically positioned so that their terminals 29 are located for firing the explosive gasoline mixture at the annular combustion chamber zone 26. The portions of 5 the spark plugs 28 remote from the spark terminals 29, are located in spaces intermediate two of the fins 23. As the piston 24 moves outwardly of cylinder 10 during its compressing stroke the gaseous fuel mixture in the combustion chamber, 10 which has been induced to swirl around the axis X—X, will continue to swirl in said zone 26, the spark plug terminals 29 are thus located in a very favorable position to obtain a good scouring action 15 of these terminals and also to advantageously cool the terminals.

The location of the spark plug is determined largely by the shape and construction of the combustion chamber, and by the character of the fuel mixture in said combustion chamber. It is 20 desirable in some instances to locate the terminals of the spark plug in that portion of the combustion chamber where the fuel mixture is relatively rich, and in engines where the fuel mixture is swirling by reason of the swirling motion induced thereto by the sleeve valve means, it is 25 found that satisfactory results are obtained by locating said spark plugs substantially as shown in the accompanying drawing.

In engines of the sleeve valve type and in particular engines of the single sleeve valve combined movement type, the sleeve intake ports are constructed for cooperative operation with the cylinder intake ports, whereby to provide opening edges which are inclined to the horizontal. 30 These inclined opening edges induce the fuel mixture introduced into the engine cylinder to swirl about the cylinder axis X—X, and thus the charge is caused to swirl in the annular chamber specified as the annular combustion chamber 35 zone 26.

It will be understood that my present invention is of particular significance with engines in which the combustible fuel mixture is swirling at relatively high velocities and in sleeve valve engines 40 it is not unusual to swirl the fuel mixture at 10,000 R. P. M. or higher, though swirls of 3,000 to 8,000 R. P. M. are usually employed, this swirl particularly influencing the character of combustible fuel mixture in the combustion chamber. 45

50 Swirling of the fuel mixture at these velocities is readily obtained in sleeve valve engines because of the inherent tendency of such engines to induce this swirl, this swirl tendency being more pronounced in sleeve valve engines of the combined movement type.

As a further feature of my invention I preferably construct either the piston, or cylinder head, or both in the illustrated embodiment, to provide a central combustion chamber zone of relatively 60 small clearance axially of the cylinder. Thus the cylinder head B is formed with a central inwardly projecting part 30 adapted to cooperate with an outwardly projecting portion 31 of the central region of the face of piston 24, Fig. 1 illustrating 65 in dotted lines the outermost position of the piston travel which forms the central zone 32 of relatively small clearance as compared with the cylinder head and piston clearance of zone 26. The provision of the restricted zone 32 facilitates the 70 swirling action of the gases in the annular zone 26 and generally improves the engine performance.

Various changes and modifications of my invention will be apparent from my disclosure and 75 it is not my intention to limit my invention to

specific combination and arrangement of parts illustrated.

What I claim as my invention is:

1. In an internal combustion engine, a cylinder, sleeve valve means associated with said cylinder and acting to induce the fuel mixture introduced into the cylinder to swirl in one direction about the cylinder axis, a cylinder head structure closing one end of said cylinder and having heat radiating fins extending across the outer face of the head structure, a piston operable within said cylinder, and a spark plug having its terminals positioned radially inwardly and adjacent the outer end of the wall of said cylinder, said spark plug having its end portion remote from its spark terminals projecting outwardly substantially axially of the cylinder from said cylinder head structure into a space intermediate two of said fins. 10

2. In an engine, a cylinder, sleeve valve means associated with said cylinder and acting to induce the fuel mixture introduced into the cylinder to swirl in one direction about the cylinder axis, a cylinder head closing said cylinder and forming an annular combustion zone with said cylinder radially inwardly and adjacent the outer end of 15 the wall of said cylinder, and a spark plug having its terminals positioned at said zone. 20

3. In an engine, a cylinder, sleeve valve means associated with said cylinder and acting to induce the fuel mixture introduced into the cylinder to swirl in one direction about the cylinder axis, a cylinder head closing said cylinder and forming an annular combustion zone with said cylinder radially inwardly and adjacent the outer end of 25 the wall of said cylinder, and a spark plug having its terminals positioned at said zone, said sleeve valve means extending into said zone. 30

4. In an engine, a cylinder, sleeve valve means associated with said cylinder and acting to induce the fuel mixture introduced into the cylinder to swirl in one direction about the cylinder axis, a cylinder head closing said cylinder and forming an annular combustion zone within said cylinder adjacent the outer end of the wall of 35 said cylinder, and a spark plug having its terminals positioned at said zone, said sleeve valve means comprising a single sleeve valve having its upper edge exposed to said zone. 40

5. In an engine, a cylinder, sleeve valve means associated with said cylinder and acting to induce the fuel mixture introduced into the cylinder to swirl in one direction about the cylinder axis, a cylinder head closing said cylinder and forming an annular combustion zone within said cylinder adjacent the outer end of the wall of 50 said cylinder, and a pair of spark plugs having terminals positioned at said zone and adapted to fire an explosive mixture at substantially diametrical points of said zone. 55

6. In an engine, a cylinder, sleeve valve means associated with said cylinder and acting to induce the fuel mixture introduced into the cylinder to swirl in one direction about the cylinder axis, a cylinder head closing said cylinder and forming an annular combustion zone within said cylinder adjacent the outer end of the wall of 60 said cylinder, and a spark plug having its terminals positioned to be swept by gas swirl around said zone. 65

7. In an engine, a cylinder, a cylinder head closing one end of said cylinder, a piston operable within said cylinder, sleeve valve means associated with said cylinder and acting to induce the fuel mixture introduced into the cylinder to swirl in one direction about the cylinder axis. 70

- 5 said piston and cylinder head together forming a combustion chamber within the cylinder having a central zone of relatively small clearance and an outer zone of relatively large clearance, said sleeve means extending into said outer zone, and a spark plug at said last zone.

6 8. In an engine, a cylinder, a cylinder head closing one end of said cylinder, a piston operable within said cylinder, sleeve valve means of the combined movement type associated with said cylinder, said piston and cylinder head together forming a combustion chamber within the cylinder having a central zone of relatively small clearance, and an outer zone adjacent the outer end of the cylinder walls of relatively large clearance, said sleeve valve means having an outer edge terminating in said outer zone.

10 9. In an engine, a cylinder, a cylinder head closing one end of said cylinder, a piston operable within said cylinder, sleeve valve means of the combined movement type associated with said cylinder, said piston and cylinder head together forming a combustion chamber within the cylinder having a central zone of relatively small clearance, and an outer zone adjacent the outer end of the cylinder walls of relatively large clearance, said sleeve valve means having an outer edge terminating in said outer zone.

15 10. In an engine, a cylinder, a cylinder head, a piston operable within the cylinder, sleeve valve means of the combined movement type associated with said cylinder, said piston having a central portion of its face relatively closely approaching said cylinder head at its outermost position of travel, said piston and cylinder head forming an annular combustion chamber zone around said piston adjacent the outer end of the cylinder walls face portion, said sleeve valve means terminating outwardly in said annular combustion chamber when in its outermost position of travel.

20 11. In an engine, a cylinder, a cylinder head, a piston operable within the cylinder, sleeve valve means associated with said cylinder and acting to induce the fuel mixture introduced into the cylinder to swirl in one direction about the cylinder axis, said piston having a central portion of its face relatively closely approaching said cylinder head at its outermost position of travel, said piston and cylinder head forming an annular combustion chamber zone within the cylinder and around said piston face central portion, and a spark plug at said annular zone.

25 12. In an engine, a cylinder, a cylinder head, a piston operable within the cylinder, sleeve valve means associated with said cylinder and acting to induce the fuel mixture introduced into the cylinder to swirl therein about the cylinder axis, said piston having a central portion of its face relatively closely approaching said cylinder head at its outermost position of travel, said piston and cylinder head forming an annular combustion chamber zone within the cylinder and around said piston face portion, and a spark plug at said annular zone, said sleeve valve means extending into said zone.

30 13. In an engine, a cylinder, a cylinder head, a piston operable within the cylinder, sleeve valve means associated with said cylinder and acting to induce the fuel mixture introduced into the cylinder to swirl therein about the cylinder axis, said piston having a central portion of its face relatively closely approaching said cylinder head at its outermost position of travel, said piston

35 14. In an engine of the air cooled type, a cylinder, sleeve valve means associated with said cylinder and acting to induce the fuel mixture introduced into the cylinder to swirl therein about the cylinder axis, a cylinder head closing said cylinder and provided with cooling fins projecting outwardly from the top thereof for exposure to an air stream, and a spark plug carried by the cylinder head, said spark plug having its terminals positioned adjacent the wall of said cylinder, said spark plug projecting outwardly from said cylinder head for exposure to said air stream flowing across the top of said cylinder head.

40 15. In an engine of the air cooled type, a cylinder, sleeve valve means associated with said cylinder and acting to induce the fuel mixture introduced into the cylinder to swirl therein in one direction about the cylinder axis, a cylinder head closing said cylinder and provided with cooling fins projecting outwardly therefrom for exposure to an air stream sweeping directly across said head in substantially a straight path, and a pair of spark plugs exposed to said air stream, said spark plugs being located remotely from the cylinder axis.

45 16. In an engine of the air cooled type, a cylinder, sleeve valve means associated with said cylinder and acting to induce the fuel mixture introduced into the cylinder to swirl therein in one direction about the cylinder axis, a cylinder head closing said cylinder and provided with cooling fins projecting outwardly therefrom for exposure to an air stream sweeping directly across said head in substantially a straight path, and a pair of spark plugs exposed to said air stream, said spark plugs being located remotely from the cylinder axis, whereby their terminals are positioned adjacent the wall of said cylinder.

50 17. In an engine of the air cooled sleeve valve type, a cylinder, sleeve valve means within the cylinder and acting to induce the fuel mixture introduced into the cylinder to swirl therein in one direction about the cylinder axis, a piston within said sleeve valve means, a cylinder head closing said cylinder and forming with the piston and cylinder an annular combustion chamber zone within the cylinder and adjacent the outer ends of the cylinder and sleeve valve means, the outer peripheral limits of said zone being defined by said cylinder walls, and a spark plug having its terminals positioned at said zone.

55 18. In an engine of the air cooled sleeve valve type, a cylinder, sleeve valve means within the cylinder and acting to induce the fuel mixture introduced into the cylinder to swirl therein in one direction about the cylinder axis, a piston within said sleeve valve means, a cylinder head closing said cylinder and forming with the piston and cylinder an annular combustion chamber zone within the cylinder and adjacent the outer ends of the cylinder and sleeve valve means, the outer peripheral limits of said zone being defined by said cylinder walls, and a spark plug having its terminals positioned at said zone, said piston relatively closely approaching said cylinder head at its central face portion with respect to the portion of its face forming said zone.

60 19. In an engine of the air cooled sleeve valve type, a cylinder, sleeve valve means within the cylinder and acting to induce the fuel mixture introduced into the cylinder to swirl therein in one direction about the cylinder axis, a piston within said sleeve valve means, a cylinder head closing said cylinder and forming with the piston and cylinder an annular combustion chamber zone within the cylinder and adjacent the outer ends of the cylinder and sleeve valve means, the outer peripheral limits of said zone being defined by said cylinder walls, and a spark plug having its terminals positioned at said zone, said piston relatively closely approaching said cylinder head at its central face portion with respect to the portion of its face forming said zone.

65 20. In an engine of the air cooled sleeve valve type, a cylinder, sleeve valve means within the cylinder and acting to induce the fuel mixture introduced into the cylinder to swirl therein in one direction about the cylinder axis, a piston within said sleeve valve means, a cylinder head closing said cylinder and forming with the piston and cylinder an annular combustion chamber zone within the cylinder and adjacent the outer ends of the cylinder and sleeve valve means, the outer peripheral limits of said zone being defined by said cylinder walls, and a spark plug having its terminals positioned at said zone, said piston relatively closely approaching said cylinder head at its central face portion with respect to the portion of its face forming said zone.

70 21. In an engine of the air cooled sleeve valve type, a cylinder, sleeve valve means within the cylinder and acting to induce the fuel mixture introduced into the cylinder to swirl therein in one direction about the cylinder axis, a piston within said sleeve valve means, a cylinder head closing said cylinder and forming with the piston and cylinder an annular combustion chamber zone within the cylinder and adjacent the outer ends of the cylinder and sleeve valve means, the outer peripheral limits of said zone being defined by said cylinder walls, and a spark plug having its terminals positioned at said zone, said piston relatively closely approaching said cylinder head at its central face portion with respect to the portion of its face forming said zone.

75 22. In an engine of the air cooled sleeve valve type, a cylinder, sleeve valve means within the cylinder and acting to induce the fuel mixture introduced into the cylinder to swirl therein in one direction about the cylinder axis, a piston within said sleeve valve means, a cylinder head closing said cylinder and forming with the piston and cylinder an annular combustion chamber zone within the cylinder and adjacent the outer ends of the cylinder and sleeve valve means, the outer peripheral limits of said zone being defined by said cylinder walls, and a spark plug having its terminals positioned at said zone, said piston relatively closely approaching said cylinder head at its central face portion with respect to the portion of its face forming said zone.
